METAL BENDING MACHINE WITH JOINTED
SWEEP ARM CARRYING A MANDREL

Frederick L. Duer, Chicago, Ill.

Application September 7, 1946, Serial No. 695,436

8 Claims. (Cl. 153—45)

1.

This invention relates to improvements in metal bending machines and has for an object to provide a machine by means of which, tubing and like materials may be bent into predetermined angular forms.

It is an object of the invention to provide a metal bending machine capable of forming a plurality of angular bends in a length of tubing or similar material without rearranging or readjusting such material on the machine preparatory to the making of individual and/or succeeding bends therein.

Another object of the invention resides in the provision of a machine of the indicated character so constructed and operable that a plurality of predetermined angular bends (bends of predetermined degrees) can be collectively effected in a length of material.

As will be readily understood and appreciated by skilled artisans, metal bars, rods, strips, tubes, etc. have been and are being bent into various shapes and angular relationships by bending machines. The indicated character of bending is effected by adjustment of the stock to be bent to a predetermined position on a bending machine, whereupon the machine is operated. Then, if a second bend is to be made in the stock, such stock is repositioned or readjusted in such machine, following which the machine is operated to effect the second bend. This method or procedure of operation is repeated as many times as are required to make the desired number of bends in a length of stock material.

Whereas, step-by-step bending of materials, in the manner stated, results in the ultimate production of a finished piece, it is a well known fact that the labor costs associated with such productions are material, especially, in products having a multiplicity of angular bends therein throughout their lengths. Moreover, in production work where a number of angular bends are formed in a length of material, considerable care and skill on part of machine operators is required to ensure accurate angular bends and similar succeeding bends. Without such care and skill by the artisan, plus the incidental time absorbing and material cost procedures, unsatisfactory productions, more generally, result.

Through the medium of my improved metal bending machine, the collective and individual forming of a plurality of angular bends of predetermined degree or degrees in and throughout the lengths of bar, rod, strip, tubing, etc., stock can be made, all without the necessity of re-adjusting such stock following its initial arrange-

2.

ment and/or engagement in the machine. In consequence, a material saving of labor and time is effected, along with proportionate reductions of production costs and a materially increased rate of production. Additionally, and most important, the production of bent devices made of bar, rod, strip, tubular and other length materials, each an accurate and faithful replica of the other, will be effected.

10 The foregoing, as well as other objects, advantages and meritorious teachings of my invention, will be in part obvious and in part pointed out in the following detailed disclosure thereof, when taken in conjunction with the accompanying drawings, it being understood that the form of the invention presented herein is precise and what is now considered to be the best mode of embodying its principles, but that modifications and changes may be made in specific embodiments without departing from its essential features.

In the drawings:

Figure 1 is a top plan view of my improved machine.

Figure 2 is a front elevation of the same with the machine bed fragmentally shown.

Figure 3 is an end elevation of the machine.

Figure 4 is a vertical transverse section taken on the line 4—4 of Figure 1, looking in the direction in which the arrows point.

30 Figure 5 is an enlarged top view of certain of the bending assemblies with another thereof fragmentally shown, following the initial placement of a length of stock material to be bent in the machine preparatory to its bending.

35 Figure 6 is a similar view in which the bending assemblies have been moved for the making of initial bends in a length of stock material, shown herein to be tubular.

Figure 7 is a similar view in which one of the 40 bending assemblies for making a succeeding bend in the length of tubular stock material is shown in an operated position, and

Figure 8 is an elevation of a length of stock material which has been bent, in two operations, to substantially U-shaped formation.

45 Referring in detail to the drawings, my improved bending machine, generally, comprises a bed or stand 1 mounting a bed plate 2 on its upper side, on which a substantially U-shaped supporting body 3 is fixedly arranged adjacent one of its ends and disposed longitudinally of the bed plate. The leg portions of the supporting body 3, as shown in Figure 4 of the drawings, are arranged in different horizontal planes and its vertical portion has a way or opening 3', of appropriate shape

3 and size, formed therein, as shown in Figures 1 and 4.

Bending assemblies 4 and 4' and 5 and 5' are mounted on the bed 1 through or by means of the supporting body 3.

The bending assemblies 4 and 4' are complementary, except, as will be seen upon reference to Figure 1, they are arranged in opposed relation. Therefore, in the pertinent descriptive matter following, reference will be made only to the assembly 4 and this will suffice for the assembly 4'.

The assembly 4 comprises a horizontally positioned bifurcated or U-shaped metal body 6 whose opposed extremities are relatively thickened adjacent their free end portions, as at 7, and formed with vertically aligned bearing openings, while its vertical basal portion has a longitudinal way 8 therein. The metal body 6, including the opposed extremities, is of angular formation (substantially dog-leg shaped). The bearing openings of the thickened end portions 7 loosely receive therethrough a cylindrical non-rotatable post 9 vertically mounted in the U-shaped supporting body 3, and, as shown in Figure 4 of the drawings, said thickened end portions 7 have more or less straddling engagement with the upper leg portion of said supporting body 3. Thus, it will be seen that a pivotal or swing mounting of the bending assembly 4 on the bed 1 is effected. If desired, non-rotatable mounting or positioning of the post 9 may be ensured by engaging a binding or locking screw 9' through an appropriate portion of the U-shaped supporting body 3 and with an adjacent portion of said post 9 (see Figure 2). A gear 10 is also loosely mounted on the non-rotatable post 9 immediately below the lower or adjacent end portion 7 of the bending assembly body 6, and is locked thereto by a coupling pin or key 11. The upper end of the non-rotatable post 9 is peripherally reduced at 12 and formed with a further reduced and screw-threaded extension 13, the purpose of which is hereinafter more fully described.

Opposed extensions or enlargements 14 and 15 (see Figures 5 to 7) are integral with the normally upper side of the body 6 in proximity to the point of its intermediate angling and have a stub-axle 16 and a non-rotatable post 17 vertically engaged therethrough. The axle 16 rotatably receives a horizontally positioned thrust roller 18. A horizontal bending and forming peripherally grooved roller 19 is non-rotatably received on the reduced portion 12 of the non-rotatable post 9, being locked thereto by a nut 20 turned onto its screw-threaded extension 13. In this particular connection, attention is directed to the fact that the thrust and bending and forming rollers 18 and 19 are in the same horizontal plane directly above the upper side of the body 6.

Bolted or otherwise fixedly connected, as at 21, to the opposite and outer end of the U-shaped and dog-leg angled body 6 is a cylinder 22 whose open inner end aligns and communicates with the way 8 in said body. A plunger 23 is slidably received in the cylinder 22, the rod 24 of which passes through a suitably packed gland in its head and has the free end thereof screw-threaded. A stop-sleeve 25 is movably received on the rod 24 adjacent its screw-threaded portion and is adjustably engaged by lock-nuts 26 turned thereto. Obviously, by turning the nuts 26 the length of the stroke of the plunger 23 in the cylinder 22, may be pre-adjusted. To the inner

5 side of the plunger 23 a rack-bar 27 is endwise fixedly connected, and as will be observed upon reference to Figure 1 of the drawings, said bar extends longitudinally from the plunger and its cylinder into meshed engagement with the teeth of the gear of the companionate bending assembly 5, hereinafter more fully described.

In order that controlled collective pivotal or swinging movement of the bodies of the bending 10 assemblies 4 and 4' may be effected, a cylinder 28 is immovably mounted on and longitudinally of the bed plate 2, as at 29. A plunger 30 is slidably received within said cylinder. To one side of the plunger, a rod 31 is fixedly connected. 15 This rod movably receives thereon a stop-sleeve 32 adjustably engaged by lock-nuts 33 turned onto its screw-threaded end 34. To the opposite side of the plunger 30 within the cylinder 28, a longitudinally disposed rod 35 is connected and 20 the remaining or outer end of the same is engaged through the adjacent head of a subordinate cylinder 36 in which a plunger 37 slidably works. A rod 38 is connected to the plunger 37 and extends, through a suitably packed way in its end, 25 longitudinally therefrom. Integral with or fixed to the free end of the rod 38 is a bar 39 having rack teeth 40 on its opposite sides. These rack teeth 40, as clearly shown in Figures 1 and 5 of the accompanying drawings, are in constant mesh 30 with the teeth of the gears 10 of the complementary though relatively opposed bending assemblies 4 and 4'. The outer and free end of the bar 39 is slidable through the way 3' in the U-shaped supporting body 3, and so, is assured 35 of predetermined and unimpeded longitudinal movement for effectually transmitting motion to the gears 10 and hence to their respective bending assemblies 4 and 4', from the cylinder received plunger 30.

40 The bending assemblies 5 and 5' provided, respectively, to the bending assemblies 4 and 4', are complementally constructed and when operatively associated with the latter, are in opposed relation (see Figure 1 of the drawings). Hence, 45 for brevity, only the assembly 5 will be specifically described; it being understood that such description will suffice for both thereof.

The bending assembly 5 comprises an arm-like body 41, suitably braced throughout its 50 length, formed or provided with an offset and sturdy thickened inner end portion 42. Vertically aligned bearing openings are formed in the free end portions of the upper and lower sides of the bifurcated end 42 and, as shown in 55 Figure 2 of the drawings, said upper and lower sides have straddling engagement with the lower side of the body 6 of the bending assembly 4. Swingable mounting of the thus engaged bending assembly 5 on and with relation to the bending assembly 4 is effected by passing the non-rotatable post 17 from the extensions 15 on the body 6 through the aligned bearing openings of the bifurcated end 42. The non-rotatable post, if desired, may be keyed or otherwise connected 60 to the extensions 15 and its upper end is extended for a suitable distance above the upper side of the body 6 where it non-rotatably receives a bending and forming peripherally grooved roller 43. The roller 43, as shown in 65 Figures 2 and 3 of the drawings, is arranged in a horizontal plane corresponding to that of the bending and forming roller 19 of the bending assembly 4, as well as that of its thrust roller 18.

The upper side of the bifurcated end 42 of the 70 arm-like body 41 is somewhat longer than its

lower side and has its free end arcuately formed and peripherally equipped or otherwise provided with gear teeth 44. These gear teeth 44 mesh with the teeth of the tangentially disposed rack bar 21. In consequence, motion from said rack bar 21, with rectilinear movement of the same, will be transmitted to the arm-like body 41 of the bending assembly 5, causing its pivotal or swinging movement with relation to the bending assembly 4 in a predetermined direction and to a predetermined degree or extent.

An integral extension or enlargement 45 is provided on one edge of the upper side of the bifurcated end 42 of the body 41 inwardly and laterally of its gear toothed end 44 and bending and forming roller 43, and has a suitably sized cylinder 46 fixed to and depending from its under side. A plunger 47 is slidably received in the cylinder and has the rod 48 thereof extended upwardly therefrom through an aligning opening in said extension 45 to a point thereabove where it mounts a thrust roller 49 normally disposed in the same horizontal plane of the bending and forming rollers 19 and 43 and the thrust roller 18, aforesaid.

The length of the arm-like body 41 of the bending assembly 5 is such that it will serve to adequately accommodate and support a mandrel 50. A cylinder 51 is supported on and longitudinally of the outer end portion of the body 41 (see Figures 1 and 2) and slidably receives therein a plunger 52, the rod 53 of which extends longitudinally of the body, from the cylinder, and has adjustable screw-threaded connection with the adjacent end of said mandrel 50, as at 53'. A guide bracket 54, or its equivalent, is mounted on the inner end portion of the body 41, suitably spaced from the cylinder 51, and suitably receives the mandrel 50 and the rod 53 therethrough, for an obvious purpose.

To limit the extent of sliding movement of the mandrel 50 and its rod 53 into a tubular body, such as designated by the reference letter T, preparatory to and/or at the time of making of a second or second operational-stage bend in said tubular body, I preferably mount, at an appropriate point on the arm-like body 41, a bracket plate 55, slotted at 56 for longitudinal adjustable connection to said body by set or locking screws 57. A dog 58 is pivoted to the intermediate portion of the bracket plate 55 and, when swung inwardly with respect to the rod 53, will, at times, abuttingly engage with the shoulder adjacent the point of connection of said rod with the plunger 52, and so, stop or limit movement of the mandrel 50 at or to the proper point.

At this point, it may be noted that suitable and usual conduits or piping and control valves (not shown in the drawings because they form no part of the invention) are supplied to the cylinders 22, 28, 36 and 46 of the bending assemblies 4 and 4' and 5 and 5', and to the mandrel cylinders 51 of the bending assemblies 5 and 5', whereby motive power (hydraulic, pneumatic, etc.) may be conducted to and from the same for effecting their controlled operation.

In operation of my bending machine, particularly, for the bending of a tube or tubing T, into a shape as shown in Figure 8 of the drawings, wherein said tubing is formed with a plurality of angular bends to accord to it a substantial U-shape with oppositely disposed lateral ends, the straight length of tubing T is placed in the machine in the position shown in Figures 1 and 2.

In such position, it will be noted that the tubing lies with portions thereof adjacent the peripheries of the bending and forming rollers 19 of the bending assemblies 4 and 4', i. e., between the same 5 and the thrust rollers 18, while outward portions thereof are peripherally adjacent and between the bending and forming rollers 43 and thrust rollers 49 of the bending assemblies 5 and 5'. To facilitate this positioning of the tubing T in the machine between and adjacent said bending and forming rollers and thrust rollers, the plunger 30 working in the cylinder 28, is moved therein to the limit of its inward position, causing the rack bar 39 to move with it and thus rotate the gears 10 of the bending assemblies 4 and 4'. Rotation of said gears 10 on their respective bearing posts 9 will be transmitted to the U-shaped body 6 and the bending assemblies 4 and 4', causing each of them to be pivotally moved or swung outwardly about or with relation to their respective bearing posts 9. Further outward swinging of the bending assemblies 4 and 4' will be effected by admitting motive fluid or like power means to the subordinate cylinder 36 15 whereby the plunger 37 slidably received therein will be thrust inwardly with respect to its cylinder, and thus, impart a second stage of rectilinear movement to the rack bar 39. This second stage movement of the rack bar 39 under influence of the subordinate cylinder 36 and its plunger 37, as explained, will transmit further outward pivotal or swinging movement to the bending assemblies 4 and 4' through their respective gears 10 and said assemblies will, thereby, 20 be positioned in the manner shown in Figure 5 of the accompanying drawings. In such positions, it will be observed, upon reference to said Figure 5 of the drawings, that sufficient clearance or space will be effected between the thrust rollers 18 and the bending and forming rollers 19 of the bending assemblies 4 and 4' and the rollers 43 of the assemblies 5 and 5' to permit free or unimpeded arrangement or placement of the tubing T in the machine and between said rollers. 25 Concurrently with such second stage movement of the assemblies 4 and 4' and 5 and 5', pressure is admitted to the cylinders 46 of the assemblies 5 and 5', whereby to effect lowering of their rods 48 and so, likewise lower the thrust rollers 49 of said assemblies to points where they will not interfere with placing of the tube T in the machine, i. e., into proper positioning with relation to the rollers 18, 19 and 43. With the tubing 30 thus placed in the machine in position for bending, motive means is admitted into the subordinate cylinder 36 from its opposite end for driving or forcing the plunger 37 outwardly therein, causing the rack bar 39 to be returned to its initial position, as shown in Figure 1, and the thrust rollers 18 and the forming rollers 43 of the bending assemblies 4 and 4' and 5 and 5' to be 35 brought into contact or abutting engagement with adjacent portions of the tubing T. Thereupon, pressure is so admitted to the cylinders 46 as to cause their rods 48 to be raised, and so, likewise raise the thrust rollers 49 of the assemblies 5 and 5' to positions where they will effectually thrust engage adjacent portions of the tube T. 40 At this time, the machine is ready for the initial bending of the tubing T. To accomplish such bending, motive means is admitted to the proper end of the cylinder 28 and in so doing, the plunger 35 slidably therein, will be driven in 45 an outward direction, whereby to swing the bend- 50 55 60 65 70 75

ing assemblies 4 and 4' inwardly to the positions shown in Figure 6 of the drawings. During this latter movement of the bending assemblies 4 and 4', driven by the rack bar 39 through the gears 10, it will be seen that those portions of the tubing T directly over or adjacent the peripheral surfaces of their bending and forming rollers 19, will be bent over and about the same. This constitutes the first stage of bending of the tubing T, and as will be noted on reference to said Figure 6 of the drawings, the tubing will have a pair of angular bends collectively effected therein. Crushing or distortion of the tubing T adjacent its points of bending over and about the bending and forming rollers 19 will be prevented by engagement of the mandrels 50 in and through the tubing to points tangential to their respective axes.

In instances of production where second stage bends or bending operations are to be effected by the machine on the tubing T arranged therein, the mandrels 50 are retracted or drawn outwardly of the angularly disposed leg portions of such tubing to points substantially tangential to the axes of the bending and forming rollers 43 of the bending assemblies 5 and 5'. Thereupon, motive power is appropriately admitted to the cylinders 22 mounted on the outer ends of the U-shaped bodies 6 of the bending assemblies 4 and 4', causing the plungers 23 therein to be slidably moved, together with their respective rack bars 27, in directions to transmit rotation to the bending assemblies 5 and 5' in directions whereby said bending assemblies 5 and 5' will be swung from the position shown in Figure 6 to the position shown in Figure 7 of the accompanying drawings. This collective pivotal movement of the bending assemblies 5 and 5', under influence of power and motion imparted thereto from the operated rack bars 27, will effect angular bending of those portions of the tubing T adjacent and engaged with the peripheral surfaces of the bending and forming rollers 43 over and about the same, as shown in Figure 7.

Obviously, the orbital paths of movement of the thrust rollers 18 and 49, during their respective periods of operation, will anchor the adjacent and engaged portions of the tubing T against relative movement, and so, ensure effectual and satisfactory bending of it about those portions adjacent and engaged with their respective bending and forming rollers 19 and 43.

To remove the multi-stage bent tubing T from the machine, motive power is collectively or otherwise suitably admitted to the cylinders 46 carried on the bending assemblies 5 and 5' supporting the thrust rollers 49. The motive power is so admitted as to cause the plungers 47 working in said cylinders to be forced downwardly therein. During such movement of the plungers along with their respective rods 48, it will be seen that the thrust rollers 49 carried on the upper ends of said rods, will be dropped or moved downwardly to points below adjacent portions of the bent tubing T. At this time, motive power is appropriately admitted to the cylinder 28 to cause rectilinear movement of the rack bar 39 in a direction opposite to that first explained. Thereby, said rack bar 38, meshing with the gears 10 of the bending assemblies 4 and 4', will be operated in directions to cause swinging or pivotal returning of the bending assemblies 4 or 4' to their initial or starting positions. By the same token, the bending assemblies 5 and 5' will be

carried with the same. The bent tubing may now be readily removed from the machine.

The bending assemblies 5 and 5' are, of course, returned to their normal or initial position by reversing operation of their respective driving rack bars 27 of the cylinders and plungers 22 and 23, respectively.

By adjustment of the stop-sleeves 25 and 32 longitudinally of their respective plunger rods 24 and 31, through appropriate turning of the lock nuts 26 and 33, it will be seen that the lengths of the working strokes of the cylinder plungers 23 and 30, may be regulated as required or desired, and therefore, that the extent of movement of the rack bars 27 and 39 may be regulated to effect pivotal or swinging movement of the bending assemblies 4 and 4', and 5 and 5' to a minute degree. In this manner, the angularity or the degree of bends effected in tubing or other lengths of stock arranged in the machine may be adjusted or varied, such as operating conditions or preference may dictate. Moreover, by so controlling the length of the working strokes of the cylinder provided plungers 23 and 30, it will be understood that succeeding bends made in tubing or other lengths of stock successively placed in the bending machine will be accurately and faithfully reproduced, i. e., one will be a faithful and true replica of the other.

Whereas, I have hereinbefore described with some degree of particularity, the improved bending machine as being used for the bending of lengths of tubing, it will be understood and appreciated by workers skilled in the art, that various forms of materials may be effectually and satisfactorily bent thereby, as for example, bars, rods, strips, etc., of metal and other materials.

I claim:

1. A bending machine, comprising a supporting bed, an arm swingably mounted on the bed, gear teeth on and about that portion of said arm swingably mounted on said bed, a bending and forming means fixedly mounted adjacent the arm in proximity to its point of pivotal mounting on said bed, a thrust means on the arm longitudinally and transversely spaced from said bending and forming means, a second arm swingably mounted on the outer and free end portion of said first mentioned arm beyond the bending and forming means and the thrust means on said first mentioned arm, gear teeth on and about the pivotally mounted end portion of said second arm, a bending and forming means fixedly mounted on said second arm in proximity to the point of its pivotal mounting on said first mentioned arm, a thrust means on the second arm longitudinally and transversely spaced from said second mentioned bending and forming means, a rack bar slidably mounted on the bed meshing with the gear teeth on said first mentioned arm for transmitting swinging motion to the same, and a rack bar slidably mounted on a portion of said first mentioned arm meshing with the gear teeth on said second arm for transmitting swinging motion thereto.

2. A bending machine, comprising a supporting bed, an arm swingably mounted on the bed, a bending and forming means on the arm, a thrust means on the arm longitudinally and transversely spaced from said bending and forming means, a second arm swingably mounted on the first mentioned arm beyond the bending and forming means and thrust means on said first mentioned arm, a bending and forming means on said second arm, a thrust means on the second arm

longitudinally and transversely spaced from said second mentioned bending and forming means, means for selectively imparting controllable pivotal motion to each of said arms, and a longitudinally adjustable mandrel mounted on said second arm adjustably movable longitudinally inwardly and outwardly with relation thereto and with relation to said first mentioned arm.

3. A bending machine, comprising a supporting bed, an arm swingably mounted on the bed, gear teeth on and about the swingably mounted end portion of said arm, a bending and forming means fixedly mounted adjacent the arm in proximity to its point of pivotal mounting on said bed and said gear teeth, a thrust means on the arm longitudinally and transversely spaced from said bending and forming means, a second arm swingably mounted on the first mentioned arm at a point beyond the bending and forming means and the thrust means on said first mentioned arm, gear teeth on and about the pivotally mounted end portion of said second arm, a bending and forming means fixedly mounted on said second arm in proximity to its point of swingable mounting on said first mentioned arm and to the gear teeth on the swingably mounted end portion of said second arm, a thrust means on the second arm longitudinally and transversely spaced from said second mentioned bending and forming means, a rack bar slidably mounted on said bed meshing with the gear teeth on said first mentioned arm, a second rack bar slidably mounted on said first mentioned arm meshing with the gear teeth on said second arm, and means on each of said rack bars for controlling the extents of their respective inward sliding movement.

4. A bending machine, comprising a supporting bed, a horizontal arm swingably mounted at one of its end on said bed, gear teeth on and about the pivotally mounted end of said arm, a bending and forming means fixedly mounted on the arm in proximity to and concentrically of its pivotal mounting on said bed, a thrust means on the arm longitudinally and transversely spaced from the bending and forming means, a second horizontal arm swingably mounted at one of its ends on a portion of said first mentioned arm beyond the bending and forming means and the thrust means on said first mentioned arm, gear teeth on and about the pivotally mounted end portion of said second arm, a bending and forming means fixedly mounted on the second arm in proximity to its point of pivotal mounting on said first mentioned arm and concentrically of the same and the gear teeth on said second arm, a thrust means on the second arm longitudinally and transversely spaced from said second mentioned bending and forming means, a rack bar slidably mounted on said bed meshing with the gear teeth on said first mentioned arm, a cylinder on the bed outwardly of said rack bar, a plunger slidably in said cylinder connected to said rack bar, a rod extending from said plunger through the outer end of said cylinder, a cylinder mounted on a portion of said first mentioned arm, a plunger slidably in said cylinder, a rack bar connected to said plunger without said cylinder meshing with the gear teeth on said second arm, a rod connected to the plunger of the second mentioned cylinder extending through and from the outer end of the cylinder, and adjustable means on each of said rods for limiting the extent of movement of the respective plungers to which they are connected.

5. A bending machine, comprising a supporting

bed, bending and forming means swingably mounted on the supporting bed, other bending and forming means swingably mounted with relation to the first bending and forming means, means for transmitting swinging motion to the first and second bending and forming means, an adjustable mandrel slidably mounted on one of said bending and forming means selectively adjustable to predetermined positions with relation to either one of said first or second bending and forming means and means engageable with said mandrel for releasably though fixedly retaining the mandrel in a selectively adjusted position with relation to either said first or second bending and forming means.

6. A bending machine, comprising a supporting bed, an arm swingably mounted on the bed, a bending and forming means fixedly mounted on the arm, a second arm swingably mounted on a free outer portion of the first mentioned arm beyond the bending and forming means on said first arm, a bending and forming means fixedly mounted on said second arm spaced from the bending and forming means on said first arm, thrust means on the second arm spaced from the bending and forming means on said second arm, means for selectively transmitting predetermined swinging motion to each of said arms, and an adjustable mandrel movably mounted on the second arm, said mandrel being selectively adjustable to predetermined positions with relation to either one of the bending and forming means on said first or second arms.

7. A bending machine, comprising a supporting bed, an arm swingably mounted on the bed, gear teeth on a portion of said arm in proximity to its pivotal mounting on the bed, bending and forming means fixedly mounted adjacent the arm in proximity to its point of pivotal mounting on the bed, a second arm swingably mounted on a portion of said first arm beyond its pivotal mounting and beyond the bending and forming means thereon, gear teeth on a portion of said second arm in proximity to its pivotal mounting, a bending and forming means fixedly mounted on said second arm in proximity to its point of pivotal mounting on the first mentioned arm, and thrust means on the second arm spaced from said second mentioned bending and forming means, a rack bar slidably mounted on the bed meshing with the gear teeth on the first mentioned arm for transmitting swinging motion thereto, and a rack bar slidably mounted on a portion of said first mentioned arm, meshing with the gear teeth on said second mentioned arm for transmitting swinging motion thereto.

8. A bending machine, comprising a supporting bed, an arm swingably mounted on the bed, a bending and forming means fixedly mounted on the bed adjacent said arm at its point of swingable mounting on the bed, a second arm swingably mounted on a portion of said first arm beyond its swingable mounting and beyond said bending and forming means, a second bending and forming means fixedly mounted on the second arm, means for selectively transmitting predetermined swinging motion to each of said arms, and an adjustable mandrel slidably mounted on the second arm, said mandrel being selectively adjustable to predetermined positions with relation to either one of the bending and forming means on said first and second arms.

FREDERICK L. DUER.
